ATTORNEY

UNITED STATES PATENT OFFICE.

OSCAR A. ZAHNER, OF ST. LOUIS, MISSOURI.

FIRE ALARM.

Application filed August 29, 1925. Serial No. 53,267.

My invention relates to improvements in fire alarms and more particularly to those fire alarms that are automatic in their action, the same being set to go off at a temperature that is dangerously above that normally existent in the particular location in which the alarm is placed.

Such alarms are not broadly new, but they are quite apt to become inoperative through their becoming clogged with dirt, dust and the like, and in those alarms using fusible wax plugs or inserts, the alarm is apt to become inefficient through the hardening of the wax through age, thus causing the wax to melt at a higher temperature than intended, and in turn causing the alarm to go off at a temperature much higher than the desired critical temperature. One of the objects of my invention is to provide an automatic fire alarm that will reset itself automatically after giving an alarm, and that will not require the replacement of fresh wax inserts or links after each alarm.

Another of the objects of my invention is to provide a fire alarm of the kind described, wherein the controlling element will be in the form of a coiled thermostatic metal, a suitable link-work being interposed between said thermostatic metal and the escapement of a clock-work mechanism to normally hold the escapement against movement, but permit movement of the latter as soon as the desired temperature is reached.

Another of the objects of my invention is to provide means for adjusting the control means for said escapement so that the escapement will be released at selectively adjustable temperatures.

The invention has among its other objects the provision of an alarm of the kind described, which shall be simple, convenient, economical, reliable, and efficient and satisfactory for use wherever found applicable.

Many other objects and advantages of the construction herein shown and described will be obvious to those skilled in the art to which this invention appertains from the disclosures herein given.

To this end my invention consists in the novel construction, arrangement and combination of parts herein shown and described, and more particularly pointed out in the claims.

In the drawings, wherein like reference characters indicate like or corresponding parts:—

Figure I is a top plan view of the device, a part of the gong being broken away in order to show the construction more clearly;

Figure II is a view in elevation of the same, showing the gong in section; and

Figure III is a detail showing a thermostatically-controlled movably adjustable electrical terminal.

In the drawings, wherein I have illustrated the preferred embodiment of my invention, there is shown a fire alarm having an operating mechanism consisting of a spring-wind clock-work mechanism indicated generally by the reference character A, the frame-work of the same comprising the parallel plates 1 and 2, of any suitable shape and material. Posts 3 connect these plates, and if desired, one end of the winding spring 4 may be fixed to one of the posts as shown. For the purpose of winding the spring, a key 5 is provided beneath the gong 11.

A train of gearing 6 is operatively connected to the winding spring, the last gear of the train engaging with an escapement 7 pivotally mounted between the plates of the frame-work by means of the arbor 8. A pin 9 is fixed to and carried by the escapement arbor 8 so as to be oscillated thereby when the escapement oscillates. Loosely connected to the end of the escapement is a clapper 10, of any desired construction, the same being adapted to strike or ring the gong 11, the latter covering the moving parts of the entire mechanism so as to substantially exclude dirt therefrom, said gong being removably mounted upon the frame-work of the clock-work mechanism by means of any suitable fastening means, as for instance by the knurled nut 12. The clapper will strike the gong intermittently, in the usual manner, when the escapement oscillates.

In order to normally hold the clapper from striking the gong, I have provided thermostatically-controlled means, said means normally holding the escapement in its locked position, but releasing the same to permit the clapper to strike the gong when the temperature in the place in which the alarm is located reaches a predeter-

mined point, and automatically returning to normal position to reset the escapement, after the critical temperature drops.

This last-mentioned means comprises an element of thermostatic metal suitable for the purpose, made in the form of a coil 13, the outer end of which is fixed to an ear 14^a struck up from one of the plates of the frame-work, as at 14, and the inner end of 10 said coil having affixed thereto a rod 15, said rod being preferably arranged substantially perpendicularly to the plates. A pin 16 is fixedly attached to the rod 15 and extends angularly thereto for a purpose to be 15 more clearly hereinafter described. It will be obvious that as the temperature rises, the coil 13 will tend to unwind or straighten out, thus partially rotating the rod 15 and the pin 16 carried thereby. 20 A double link 17-18 is interposed between the pins 9 and 16, one of the ends of each link being slotted as shown, the slots being preferably closed. A second link 19 is pivoted at one of its ends to the adjacent 25 ends of the link 17-18, the other end of the link 19 being pivotally mounted between ears 20 preferably struck up from one of the plates of the frame-work. A leaf spring 21 is fixed at one end to one of the 30 plates, the other end of the spring pressing against the link 19 in the manner shown.

From the foregoing it is obvious that, whenever the thermostatic element 13 is actuated under the influence of heat, the pin 35 16 will swing in a clockwise direction (in the embodiment shown), thus forcing the link 17-18 toward the right, and releasing the pin 9 from its locking engagement with the escapement. In this position the escapement may freely oscillate, causing the alarm to be given by the clapper striking the gong. As soon as the temperature drops, the thermostatic element will automatically contract to its normal position, and the other parts, 40 including the link-work and escapement will again be in their normal locked position, the spring 21 assisting in bringing the parts to their normal positions, in which position the pin 9 will be held in locked position against 45 the inner end of the closed slot of the right hand member of the link 17-18.

It is quite desirable that some manner of adjustment be provided whereby the alarm may be set to go off at selectively adjustable 50 temperatures, for it is obvious that if the alarm were originally intended to go off at a temperature of say 110 degrees it would be acceptable for use in the living rooms of a house, but would cause false alarms if it 55 were placed in another part of the house, as for example in the furnace room. In order to provide this adjustment, the link 17-18 is preferably made so that one of the two members, as for instance the member 18, 60 is made of two parts, one slidably longitudi-

nally relatively to the other and held in adjusted relation by means of some suitable means such as screws or the like. In this manner, the effective length of the double link is varied, so that if the alarm is set for 70 one of the higher temperatures of the range of adjustment, the pin 16 must travel a greater distance, or with some play, before it strikes the end wall of the slot of the link member 18, thus moving the double link to 75 the left to release the escapement. Any desired markings indicating the various temperature adjustments may be provided upon the link 17-18, as shown.

Thus it will be seen that I have provided 80 an automatic fire alarm that will be positive in its action, will have no parts tending to deteriorate through inaction, does not require the replacement of inserts, fuses or the like, and will function efficiently at all times 85 and through a range of adjustments.

Where the alarm is installed in a place in which the gong might not be heard, as for instance in a warehouse or factory, it is desirable to also inform a central office or 90 watchman of the fact of the fire, and for this purpose an electric signal may be constructed as part of the alarm, the signal, wiring and source of electrical energy being shown diagrammatically in the drawing. 95

The frame-work of the clock-work mechanism may constitute one of the electric terminals of the circuit, and the other terminal may be mounted so as to be movably adjustable relative to the pin 16, as shown. The 100 latter terminal is suitably insulated from the framework as by the fibre pin 25, and is held in adjusted position by any desired means, as by the screws 24. Markings similar to those upon the link 17-18 may be 105 provided for properly positioning the adjustable terminal 23.

The signal S will be actuated when the terminal 23 is engaged by the pin 16 to close the circuit, thus indicating that the pre-determined degree of heat in the vicinity of the coiled thermostatic metal element 13 has been reached.

It is obvious that the electrical signal S may be used either in conjunction with the 115 mechanism operating the escapement, or operated in combination with a thermostatic coil alone.

Having thus described my invention, it is obvious that various immaterial modifications may be made in the same without departing from the spirit of my invention; hence I do not wish to be understood as limiting myself to the exact form, construction, arrangement and combination of parts 120 herein shown and described, or uses mentioned.

What I claim as new and desire to protect by Letters Patent is:—

1. In an automatic fire alarm, the combi- 130

- nation with a clock-work mechanism, of an escapement for operating a gong, and means for normally holding said escapement in locked position and for releasing the same
- 5 at a predetermined temperature, said means comprising a coil of thermostatically controlled material, a rod fixed to and carried by said coil, a plurality of slidably interconnected links operatively engageable directly between said rod and escapement, and means for varying the effective length of said links so that the latter may be operatively engaged by said rod at selectively adjustable temperatures, whereby said
- 10 escapement will be released by said links at selectively adjustable temperatures.
2. In an automatic fire alarm, the combination with a clock-work mechanism, of an escapement, a coil fixed at its outer end to the frame-work of said mechanism and carrying a rod at its inner end, a pin on said rod, a pin fixed to said escapement, an adjustable link engaging between said pins
- 15 whereby the effective length of said link may be varied, and means for yieldably 25 pressing said link toward said first-mentioned pin.
3. In an automatic fire alarm, the combination with a clock-work mechanism, of a clapper-operating escapement, a pin carried by said escapement, a coiled thermostatic-metal element fixed to the frame-work of said clock-work mechanism, a rod carried by said element so as to partially rotate when the element is actuated under the influence of temperature changes, a pin carried by said rod, a link engaging said pins at opposite ends, means for adjusting the effective length of said link, a second link pivoted intermediate the ends of said first-named link and pivotally connected to the frame-work of the clock-work mechanism, and means for yieldably maintaining the end of said first-mentioned link in engagement with its adjacent pin.

OSCAR A. ZAHNER.
